UNITED STATES PATENT OFFICE.

RODNEY W. GODDARD, OF WELLSTON, OHIO.

FOWL-COOP.

SPECIFICATION forming part of Letters Patent No. 313,319, dated March 3, 1885.

Application filed June 28, 1884. (No model.)

To all whom it may concern

Be it known that I, RODNEY W. GODDARD, of Wellston, county of Jackson, Ohio, have invented a new and Improved Fowl-Coop, of which the following is a full, clear, and exact description.

The object of my invention is to provide a new and improved fowl-coop which is so constructed that it can be adjusted to form compartments of different sizes.

The invention consists in the peculiar construction and arrangement of parts, as herein-after fully described, and pointed out in the claims.

15 Reference is to be had to the accompanying drawings, forming part of this specification, in which similar letters of reference indicate corresponding parts in both figures.

Figure 1 is a longitudinal elevation of my 20 improved fowl-coop, parts being broken out; and Fig. 2 is a cross-sectional elevation of the same.

The coop A is made of slats, and is provided with legs B. A transverse partition, C, 25 is provided at each lower corner with a forked clip, D, in which a flanged wheel, E, is pivoted. A bar, F, projects from the middle of the partition C, and extends through an aperture in one end of the coop. The bar F is

30 provided with an offset shoulder or stop, G, a distance from the partition C about equal to the length of the coop. The coop is provided with a door, H, at each end. At each side of the floor of the coop track-strips J are ar-

35 ranged, on which wheels E run. A feed trough, K, is arranged at each side of the floor outside of the coop. The partition C divides the coop into two compartments, of which one may be large, the other small, or both may be of the 40 same size. By means of the bar F the parti-

tion can easily be moved to any desired part of the coop, according to the sizes of the compartments desired in the coop. Different kinds of fowls can be kept in the two compartments, or fowls of different sizes can be kept in the two compartments.

If fowls are to be caught, they are forced to one end of the coop by moving the partition toward the corresponding end of the coop, the corresponding door H of the coop A being opened.

The fowls can be fed very easily by means of the trough. As the bar F projects through the end of the coop, it holds the partition in a vertical position. The bar F also serves as a roost for fowls.

I am aware that a coop provided with a movable partition sliding on guides and operated by a bar at the top of the coop is old, and I therefore do not claim such invention.

Having thus described my invention, I claim as new and desire to secure by Letters Patent—

1. The combination, with a fowl-coop, of a movable partition and a rod rigidly attached to the said partition and projecting through the coop, substantially as herein shown and described, whereby the rod is made to serve the double purpose as a means for operating the partition and as a roost, as set forth.

2. The combination, with a coop provided with track-strips on its bottom, of the movable partition C, provided with the wheels E, and the rod or bar F, rigidly secured to the partition and projecting through the coop, substantially as herein shown and described.

RODNEY W. GODDARD.
